US00D726676S

(12) **United States Design Patent**
Park et al.

(10) **Patent No.:** US D726,676 S
(45) **Date of Patent:** ** Apr. 14, 2015

(54) **MOBILE PHONE**

- (71) Applicant: **LG Electronics Inc.**, Seoul (KR)
- (72) Inventors: **Sangmin Park**, Seoul (KR); **Seunghoon Ryu**, Goyang-si (KR); **Jonghak Lee**, Cheonan-si (KR); **Euisseok Lee**, Seoul (KR)
- (73) Assignee: **LG Electronics Inc.**, Seoul (KR)
- (**) Term: **14 Years**

(21) Appl. No.: **29/480,300**

(22) Filed: **Jan. 24, 2014**

(30) **Foreign Application Priority Data**

Jul. 26, 2013 (KR) 30-2013-0038913

(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line in FIG. 7 depicts a portion of the mobile phone that forms no part of the claimed design.

1 Claim, 7 Drawing Sheets
